SIMON KAUFMAN, OF FAIRBURY, ILLINOIS.

Letters Patent No. 83,973, dated November 10, 1868.

IMPROVEMENT IN STAYS FOR COLLARS.

The Schedule referred to in these Letters Patent and making part of the same.

To all whom it may concern:

Be it known that I, SIMON KAUFMAN, of Fairbury, in the county of Livingston, and State of Illinois, have invented a new and useful Improvement in Detachable Stays for Paper and Linen Collars; and I do hereby declare that the following is a full, clear, and exact description thereof, which will enable those skilled in the art to make and use the same, reference being had to the accompanying drawings, forming part of this specification.

This invention relates to improvements in the method of staying and supporting paper and linen collars, whereby their durability is greatly increased; and it consists in the application of a detachable flexible stay and fastening-band to the collar, made of any suitable material, and constructed as hereinafter described.

Figure 1 is a perspective view of a collar provided with my improved stay.

Figure 2 is a section of the same through the line *xx*. Similar letters of reference indicate corresponding parts.

A represents the collar.

B is the stay.

C is the interior band, by which the stay is fastened to the collar.

At the ends of the stay B there are button-holes, *d*, of linen or other suitable material, and the fastening-band C is attached thereto at the ends.

The collar, being folded or doubled, as seen in the

drawing, and as they are usually made, is secured to the stay by the fastening-band C, which is enclosed with the fold, as seen, while the stay itself forms the inner wearing-surface of the collar.

The stay and the collar may be attached together by small rivets, as seen at *e*, if desired.

The stay B, as well as the inner band C, may be made of metal of any kind, or of rubber or wood, or of any other suitable material, and the stay may be covered with silk, linen, or other material, if desired.

By this method of staying and fastening the collar, injury from perspiration is prevented, there are no button-holes to tear out, and the collar is consequently made durable.

To the inner side of the stay B there is a linen button-hole loop, *f*, attached, for fastening the collar to the shirt-band at the back of the neck.

The stay and fastening-band C, thus formed and secured together, may be used for any length of time, as the collar is attached or removed with the greatest facility.

I claim as new, and desire to secure by Letters Patent—

The detachable inner stay or lining B, and the narrow detachable band C, applied to the collar A as described and shown, for the purposes specified.

SIMON KAUFMAN.
